UNITED STATES PATENT OFFICE.

DANIEL ECKHAFT, OF NORTH BEND, NEBRASKA.

FASTENER.

1,252,892.

Specification of Letters Patent.

Patented Jan. 8, 1918.

Application filed August 13, 1917. Serial No. 186,003.

To all whom it may concern:

Be it known that I, DANIEL ECKHAFT, a citizen of the United States, residing at North Bend, in the county of Dodge, State 5 of Nebraska, have invented a new and useful Fastener; and I do hereby declare the following to be a full, clear, and exact description of the invention, such as will enable others skilled in the art to which it applies 10 to make and use the same.

This invention relates to an improved button or fastener for garments and the like, and one of the objects of the invention is to provide an improved button or fastener constructed from a single length of spring wire and having prongs to permanently or detachably connect the button or fastener to one side of the garment, and provided with a head to engage a button hole opening of 20 the other side of the garment.

A further object of the invention is to provide a simple, and efficient fastener or button having improved and practical feature of construction, and which may be manufactured for a small cost and sold at a reasonable profit.

In practical fields the details of construction may necessitate alterations falling within the scope of what is claimed.

30 The invention comprises further features and combination of parts as hereinafter set forth shown in the drawings and claimed.

In the drawings:—

Figure 1 is a view in perspective of the 35 improved button or fastener constructed in accordance with the invention.

Fig. 2 is a sectional view on line 2—2 of Fig. 1, showing the opposite sides or portions of the garment in section.

40 Fig. 3 is a plan view of the button or fastener.

Referring more especially to the drawings, it is to be observed that the button or fastener is constructed from a single length of spring 45 wire turned or bent circular on itself substantially midway its end, to form a circular or ring shaped button or fastener head 2. The portions of the end parts of the wire at one side of circular or ring shaped head 50 are bent as shown at 3, and the parts 4 of the wire beyond the bends 3 are extended inwardly radially of the head 2 of the button or fastener, thereby forming guards. The opposite end portions of the wire beyond the 55 parts 4 are bent upon themselves as shown at 5, and beyond the bends 5, the end portions

of the wire are extended radially outwardly, thereby forming additional guard 6. These guards are disposed on a plane offset from the plane of head or circular ring 2. The 60 end portions of the wire beyond the guards 6 are bent as shown at 7, and then merge into the prongs 8, which have their terminals 9 pointed or sharpened. The bends 5 and the guards 4 are disposed close together, in fact 65 they firmly contact and are designed to remain in contact. However, the guards 4 are in parallelism to each other, as shown in plan view of Fig. 3. The guards 6 beyond the bends 5 are arranged V-shaped, as shown 70 in plan view in Fig. 3, while the prongs 8 are likewise arranged V-shaped relative to each other. In using the button or fastener the prongs 8 are brought together, and their sharpened ends are passed or inserted 75 through one side 10 of a garment, as shown at 11 until the opening in the garment will engage the bends 7, then the prongs 8 are allowed to spring apart, so as to securely connect the fastener or button to the garment. If need be the prongs 8 may be reinserted through the part 10 of the garment, and returned through the garment and bent in order to render the fastener secured more permanently. The other side 12 of the garment is provided with a button hole 13, through which the circular head or ring 2 may be inserted, until the end 14 of the button hole engages or contacts with the bends 5 of the fastener, whereby the circular head 90 or ring of the fastener may engage on the outer face of the part 12 of the garment, and also so that the part 12 of the garment may engage between the guards 4 and 6, as shown clearly in Fig. 2, thereby preventing 95 accidental displacement or disconnection of the part 12 of the garment. It is to be noted that owing to the opening in the part 10 of the garment engaging the bends 7, the garment is prevented from pulling in one 100 direction or the other and consequently detaching the garment. Since one end 14 of the button hole 13 engages the inner parts of the bends 5, the part 12 of the garment is prevented from moving in the direction 105 of the arrow.

The invention having been set forth what is claimed as new and useful is:—

1. A button being constructed from a single length of spring wire, curved or turned 110 circular on itself midway its ends to form a ring shaped head, said head at one side

2
having the wire bent to form guards extending substantially radially toward and adjacent the center of the head, said guards at the center of the head being bent to form additional guards offset from the first guard, said second guards extending radially and arranged V-shaped, said second guards having their wire portions bent upon themselves, and beyond said last bend, said wire portions terminating in yieldable prongs arranged V-shaped to each other and having their extremities sharpened.

2. A button being constructed from a single length of spring wire curved or turned

on itself midway its ends to form a ring 15 shaped head, said head having radial guards, said guards terminating in additional guards offset from the first guards, and the second guards terminating in spring prongs having sharpened extremities.

20

In testimony whereof I have signed my name to this specification in the presence of two subscribing witnesses.

DANIEL ECKHART.
